UNITED STATES PATENT OFFICE

106,325

DESIGN FOR A BIER

Maxwell E. Ramsey, St. Louis County, Mo.

Application August 16, 1937, Serial No. 71,115

Term of patent 3½ years

To all whom it may concern:

Be it known that I, Maxwell E. Ramsey, a citizen of the United States, residing in the county of St. Louis, State of Missouri, have invented a new, original, and ornamental Design for a Bier, of which the following is a specification, reference being had to the accompanying drawing forming a part thereof, in which—

Fig. 1 is a plan view of a bier showing my new design.

Fig. 2 is a side elevation.

Fig. 3 is an end elevation.

I claim:—

The ornamental design for a bier, as shown.

MAXWELL E. RAMSEY.
